CLAIMThe ornamental design for an electric toothbrush, as shown
and described.**DESCRIPTION**

FIG. 1 is a perspective view of an electric toothbrush;

FIG. 2 is a front view thereof;

FIG. 3 is a left side view thereof;

FIG. 4 is a rear view thereof;

FIG. 5 is a right side view thereof;

FIG. 6 is a top plan view thereof; and,

FIG. 7 is a bottom plan view thereof.

The broken lines depict portions of an electric toothbrush
and form no part of the claimed design.**1 Claim, 4 Drawing Sheets**| (56)	References Cited
